Inventor.

UNITED STATES PATENT OFFICE.

ROBERT WERNER OBERHOFFER, OF YORK, ENGLAND.

TUNING-PEG OF VIOLINS OR LIKE INSTRUMENTS.

1,135,314.

Specification of Letters Patent.

Patented Apr. 13, 1915.

Application filed August 31, 1914. Serial No. 859,342.

To all whom it may concern:

Be it known that I, ROBERT WERNER OBERHOFFER, a subject of the King of Great Britain and Ireland, residing at York, in the county of York, England, have invented certain new and useful Improvements in or Relating to the Tuning-Pegs of Violins or like Instruments, of which the following is a specification.

10 This invention relates to means for preventing the strain on the strings from pulling around the pegs in the peg holes, and thus allowing the strings to become slack or flat, *i. e.* out of tune.

15 More particularly the invention consists of improvements in that type of means for the above purpose, in which one of the two peg holes is enlarged and provided with a brake ring or socket, adapted to grip the peg and prevent its rotation in the slackening direction.

The invention is illustrated by the accompanying sheet of drawings, to which reference is had in the following description.

20 25 Figure 1 is an outside view of the peg with the brake tube in position. Fig. 2 is an outside view of the peg without the brake tube. Fig. 3 is a longitudinal section, and Figs. 4 and 5 are end views of the brake tube.

For the sake of clearness, the last three figures have been drawn to an exaggerated scale.

25 30 *a* indicates the shank of the peg, and a slightly tapered or coned sleeve *b* is pinned or otherwise secured to the peg close to its head supplying said shank with an operative tapering surface, but of course removable for substituting another sleeve, or whenever such operation is needed for other reasons.

According to this invention, this coned sleeve *b* fits within a brake ring *c*, which is formed as a spiral or helical coil of round wire, and for which I find galvanized round wire most suitable; the interior of the ring being preferably slightly tapered to correspond to the taper of the sleeve *b*. This spiral coil *c* fits within the cylindrical end *d* 45 50 of the brake tube *e*, being received in a recess formed by the enlargement of the bore of said tube, its inner end being secured to the tube *e* about the rabbet *f* by soldering or forming a recess in the rabbet to receive the end of the wire, or other suitable means. The other end of the coiled wire is held in

position by beading *i. e.* bending the outer end of the tube over inward, so as to form a retaining rim *g*, which covers only about half the thickness of the wire. The portion *h* of the tube is screwed into the enlarged peg hole of the instrument at thumb piece side of the peg; for which purpose the middle of the brake tube is provided with a milled or as shown a hexagonal collar *i*. The peg itself may be of any kind of hard wood or vulcanite.

j indicates the part of the neck of the instrument which is recessed, to expose the middle portions of the shanks of the pegs and to allow the upper ends of the strings to be connected to the pegs.

Owing to the brake coil *c* being formed of round wire, it bears on the sleeve *b* on a long closely spiral line, which gives it a much greater gripping power than a longitudinally split cylinder or cone, or a broad spiral band, and gives a fine adjustment of the binding pressure for a given angular twist of the peg.

The peg is passed through the coiled wire into the opposite hole of the head of the instrument. When pushed in, the peg is gripped by the coiled wire in the direction in which the string pulls, but not in the opposite direction. When the peg is drawn out of the tube for about one thirty second of an inch, it can be turned in either direction. The string is passed through a small hole in the cylindrical portion *a* of the peg and tuned up in the ordinary way.

The invention offers the following advantages:—The ease with which the pegs can be worked in either direction enables the weakest hand to manipulate them. The pegs cannot slip in the direction in which the string pulls. The pegs cannot get jammed. The pegs can be handled with ease while using the bow. The pegs can be fixed to the best class instrument without damaging or disfiguring the head of the instrument.

It has been previously proposed to fit the pegs of string musical instruments with a conical tube or sleeve, and to provide short cylinders or cones in the thumb piece side of the instrument, split longitudinally, or to form a broad spiral band. I do not therefore claim such but:—

What I do claim and desire to secure by Letters Patent is:—

1. A violin tuning-peg having a shank, in combination with a sleeve fixed on said

shank and slightly tapered externally, a
5 brake tube having a recess formed by an en-
largement of its bore, an annular shoulder
at the inner end of said recess and an in-
10 ternal bead at the outer end of said recess,
and a brake ring consisting of a tapering
helix of wire fitted in said recess between
said brake tube and said sleeve to act fric-
tionally on said peg, said helix bearing at its
15 inner end against said shoulder and fastened
to the said tube in proximity to said shoul-
der, also having its outer end held by said
bead against expansion substantially as set
forth.

15 2. A violin tuning-peg having a shank
provided with a tapering surface, a brake

tube having a recess formed by an enlarge-
ment of its bore and an internal annular
bead at the outer end of said recess, and a
20 helical tapered brake ring in said recess in-
terposed between said surface and said tube,
fastened to the latter at one end and held at
the other end by said bead against expan-
sion substantially as set forth.

In testimony whereof, I have signed my 25
name to this specification in the presence of
two subscribing witnesses.

ROBERT WERNER OBERHOFFER.
